BOOT

Charles H. Baker, Providence, R. I.

Application January 4, 1951, Serial No. 13,671

Term of patent 14 years

(Cl. D7—4)

To all whom it may concern:

Be it known that I, Charles H. Baker, a citizen of the United States, residing at Providence, in the county of Providence and State of Rhode Island, have invented a new, original, and ornamental Design for a Boot, of which the following is a specification, reference being had to the accompanying drawing, forming part thereof.

The figure is a perspective view of a boot, showing my new design, the opposite side presenting substantially the same appearance as the side shown except for the absence of the representation of a horse and rider.

I claim:

The ornamental design for a boot, substantially as shown and described.

CHARLES H. BAKER.
